UNITED STATES PATENT OFFICE

PETER A. SOLEM, OF ROCKFORD, ILLINOIS

SANDING MACHINE

Application filed October 16, 1925. Serial No. 62,694.

This invention relates in general to abrading machinery and is particularly concerned with sanding machines of the endless bed type which employ rotating sanding or 5 abrading drums or cylinders.

In machines of the kind mentioned, the drums are usually given a positive, oscillating, endwise movement to secure a smooth finish on the stock operated upon. One of 10 the principal objects of the present invention is to provide an improved means for accomplishing the oscillating movement which imposes no weight on the drum shafts, such as ordinarily caused uneven contact of the 15 drums with the stock because of a whipping action produced at the free end of the drum shafts, and was furthermore a cause of quick wearing of the bearings of the drum shafts.

It has also been the custom to provide 20 separate motors for the separate drum shafts, usually coupled to the shafts in such a way as to permit adjustment of the elevation of the abrading drums relative to the work. This usually resulted in the motor armature 25 shaft being considerably out of line with the drum shaft, giving poor power transmission, imposing heavy loads on the shaft bearings, and resulting in noisy operation, while at the same time necessitating separate supporting 30 brackets for the motors and greater over-all dimensions of the machine as a result of the intermediate drive couplings. A further object of this invention is to eliminate these 35 objectionable features of previous machines by the provision of built-in motors giving direct drive for the drum shafts. As a result of the rotors being part of the drum shafts, the motor remains in line with the 40 drums whether the heaviest or lightest cuts are made. Greater compactness and a considerable reduction in the over-all dimensions are secured and a saving in floor space is effected.

45 Still other objects and advantages of the present invention will be discussed more fully in the following detailed description in which reference is made to the accompanying drawings, wherein—

50 Fig. 1 is a side elevation of a sander of

the endless bed type incorporating the improvements of my invention;

Fig. 2 is a transverse section through the machine and is taken on the line 2—2 of Fig. 1 looking in the direction of the arrows, 55 portions of the drum and frame being broken away to conserve space in the drawings;

Fig. 3 is an enlarged fragmentary sectional detail of the motor housing and its mounting, an intermediate portion of the shaft for the 60 drum and armature being broken away at the armature;

Fig. 4 is a similar enlarged sectional detail taken at the opposite end of the shaft for the drum and armature and showing the connection with the rocker arm; and 65

Fig. 5 is an enlarged sectional detail of one of the eccentrics for actuating the rocker arms and is taken on the line 5—5 of Fig. 2 looking in the direction of the arrows. 70

Throughout the views the same reference numerals are applied to corresponding parts.

The sanding machines of the type to which the present improvements are intended to be applied usually comprise a base 6 having 75 heavy upright side frame pieces 7 and 8 extending therefrom and suitably fixed together in spaced relation. The frame provides supports for ways over which an endless bed 9 is arranged to move. The bed 9 consists of 80 steel slats with rubber pads secured thereon, the slats being in turn secured on roller chains operating on sprockets having bearings at 10 and 11 at opposite ends of the machine. The driving of the bed is through 85 the intermediary of suitable transmission from a shaft 12 bearing in the frame of the machine and suitably driven by a motor supported on a bracket at the side of the machine. The shaft 12 is shown in section and 90 the motor referred to is not shown. A pulley 13 suitably mounted on the shaft 12 is provided for driving pulleys 14 and 15. The pulley 14 by virtue of its position above the bed 9 is arranged to drive a brush for cleaning the stock passing out of the machine and the pulley 15 by virtue of its position below the bed is arranged to drive a brush for 95 cleaning the under side of the bed 9. The belt 16, passing about the pulleys referred 100

to, has an idler take-up pulley 17. A plurality of abrading drums 18, 19 and 20 operate over the bed 9 and are driven individually by motors 21, the motors being controlled singly or collectively to give a one, two, or three drum machine, as desired, and to permit any one or more or all of the motors being started or stopped as desired. A plurality of pressure bars 22 are provided between the abrading drums which have polished under faces for the passage therebeneath of the stock operated upon. The abrading drums are capable of adjustment as to elevation for light or heavy cuts, usually by the simultaneous adjustment of the elevation of the drum shaft bearings, by the operation of worms 23 on the ends of shafts 24. The latter are fitted with hand wheels 25 for convenient manual operation from the side of the machine. The worms 23 mesh with worm wheels 26 to operate jack screws 27 to raise and lower the shaft bearings relative to bosses 28 provided on the frame of the machine. Usually the first drum of the set is given simple rotation for the initial rough finishing cut. In this case, the drum 18 is arranged for simple rotation at the intake end of the machine. The other drums 19 and 20 are arranged to have endwise oscillation or reciprocation during rotation. By this compound movement it has been found that the grade of finish on the stock is highly improved as the fibers of the wood are not drawn or strung out and left in loose fuzz or fur on the surface of the stock. The drums are usually oscillated by rocker arms or beams 29 which have a suitable thrust bearing connection with the drum shafts. The rocker arms are suitably driven by a direct gearing connection with the shaft 12, consisting of bevel gears 30 and 31. The gear 31 is fixed on the shaft 32, which operates eccentrics, as will presently appear, to communicate a rocking motion to the arms 29. In this way the oscillating motion of the drums with the drum shafts occurs only during the feeding movement of the endless bed 9, that is, during the normal operation of the machine. For the most part, the foregoing arrangement is commonly employed in sanding machines of this type and no invention is claimed therein except in so far as the improvements hereinafter referred to are tied up with this arrangement.

Referring now more particularly to Fig. 2, the drum 19, or for that matter the drum 20, is mounted on a shaft 33 supported in bearings at 34 and 35 on the frame pieces 7 and 8 at opposite ends of the drum. According to the present invention, the housing 36 of the motor 21 is supported in the bearing 35 in a manner more particularly described hereinafter for adjustment as to elevation simultaneously with the bearings 34 and 35. The shaft 33 is in a single con-

tinuous piece without the interposition of a coupling or any intermediate transmission for the driving of the drum shaft from the armature shaft, since the rotor or armature shaft is integral with the drum shaft. This improvement thus broadly defined, it will be appreciated, accomplishes several highly desirable advantages. First of all, it is definitely insured that the armature and the drum will remain in line at all times regardless of whether a heavy or light cut is being made, the two being kept in the same relation to one another in any state of adjustment. Furthermore, the mounting of the motor housing on the same vertically adjustable support with the shaft bearing insures keeping the same relation between the armature and its field coils in the housing, regardless of the amount of adjustment. The directness of the driving connection resulting from the shaft for the armature and drum being in one piece gives smooth and noiseless operation. There is avoided the pounding and vibration at the coupling which, besides being noisy, was a contributing factor in the wearing out of the drum shaft bearings. The arrangement conduces toward the best obtainable compactness and the over-all dimensions are very much reduced so that less floor space is required. A saving in material and a reduction in weight, as well as an appreciable saving in cost, are more or less obvious results of the improvements referred to.

The shaft 33 has an integral extension, as shown at 37 in Fig. 4, for the mounting thereon of a thrust collar 38, which has a pivotal connection with the rocker arm 29 at 39 in trunnions provided on the forked end 40 of the rocker arm. The rocker arm 29 is pivoted at 41 to a link 42, which in turn is pivoted at 43 on a bracket 44 bolted to the side of the adjacent frame piece 7. The bracket 44 provides a ledge at 45 on which one end of a coiled compression spring 46 rests, while its other end is in contact with the under side of the link 42. The lower end of the arm 29 is pivoted at 47 to a link 48 having a split strap end 49 enclosing an eccentric 50 secured on the shaft 32, as by means of a tapered pin 51 (see Fig. 5). The shaft 32 is supported in bearings provided in brackets 52 on the side of the frame piece 7. The eccentric 50 and the end 49 of the link 48 are maintained in proper relation by a collar 53 secured on the end of the shaft 32 by a tapered pin 54. It will appear that the weight of the rocker arm 29 is substantially counterbalanced by the compression of the spring 46 and none of the weight of the arm is imposed on the shaft 33. The arm is in floating relation to the collar 38 and the shaft 33. This avoids the deflection of the projecting end of the shaft and eliminates the whipping action and consequent vi-

bration, which in previous machines resulted in a slight chatter or tremor of the abrading drum, or at any rate destroyed its smooth and even contact with the stock being operated upon. The links 42 and 48 also permit the vertical adjustment of the drums but the adjustment is usually so slight as not to affect the counterbalancing action of the springs 46. Just as the elimination of intermediate coupling connections between the drum shaft and the armature shaft is of advantage, so also is the provision of a vibrationless and smoothly operated oscillating drive. Both improvements contribute toward considerable improvement in the grade of the work produced by the machine. They also are factors in prolonging the life of the bearings for the drum shafts and in this way reduce operating costs and give generally better efficiency. The provision of eccentrics 50 as separate pieces assembled on the shaft 32 enable cheap and easier replacements. The take-up bolts on the split strap ends of the links 48 permit compensating for wear so that a close working fit for the links on the eccentrics 50 can be maintained at all times.

Referring for the present more particularly to Fig. 3, it will be noted that the housing 36 of the motor 21 has the bell ends 55 and 56 providing spaced armature shaft bearings. The bell end 55 is bolted to the bearing 35 as indicated at 57. A cap 58 bolted on the bearing 35 positions an outer ball race member 59 between the hollow neck 60 thereof, and a similar hollow neck 61 on the bell end 55 of the motor housing. The race member 59 and the necks 60 and 61 are all received snugly within the bore 62 of the bearing 35, and the race member 59 is held stationary between the necks 60 and 61 in an obvious manner. Anti-friction balls 63 operate between the outer race 59 and an inner race 64. The race 64 is of elongated collar form and has a sleeve 65 slidable therein. The sleeve 65 is fixed, as by means of a pin 66, against rotation relative to the shaft 33, the pin 66 being received in a notch 67 provided at the end of the sleeve 65 where the sleeve comes in contact with a shoulder 68 provided by an enlargement in the diameter of the shaft 33. It will appear that the rotation of the shaft 33 with the sleeve 65 and the inner race member 64 is permitted and is rendered almost frictionless by the provision of the balls 63. At the same time, the telescoping relation of the sleeve 65 in the inner race 64 permits the oscillation of the shaft 33 with the abrading drum as previously described. This feature is covered in my co-pending application Serial No. 416,523 filed December 26, 1929. The lubrication of the sliding joint between the sleeve and the race is induced by rings 69 dipping in the oil in the bottom of the chamber provided about the shaft within the hollow necks 60 and 61.

The lubricant is retained in the chamber referred to by packing provided at 70 in the cap 58 and bell piece 55.

The armature core, the end of which appears at 71, is suitably splined on the shaft 33 and rests in engagement with a shoulder afforded by an enlargement of the diameter of the shaft 33. A spacing sleeve 73 abuts against the end of the armature core 71 at one end and at its other end abuts against the adjacent end of the bearing sleeve 65, thereby keeping the sleeve 65 in proper relation to its ball bearing in an obvious manner. The sleeve 73 is preferably of the same diameter and of the same length as the sleeve 65 to be interchangeable therewith. For this reason, it is also provided with a notch 67 in one end thereof to receive the pin 66 when the sleeve 73 is substituted for the sleeve 65. The purpose in this provision is to obviate having to shut the machine down for an extended period in the event the sleeve 65 becomes worn to any appreciable degree. With the spacing sleeve substituted for the bearing sleeve and the bearing sleeve in turn performing the function of the spacing sleeve, the machine may be kept in service and necessary replacement sleeves ordered from the manufacturer of the machine or otherwise made to have in readiness when another replacement is necessary. This feature is also covered in the copending application mentioned above. The stepping in the diameter of the shaft toward the outer end affording the shoulders at 68 and 72, etc., enables the removal of the parts and easy replacement thereof.

The outer end of the shaft 33 is received in a bearing held in the bell end 56 of the motor housing 36. A cap 74 is bolted to the bell end 56, as shown, and clamps an outer race 75 in place. The anti-friction bearing balls 76 operate between the outer race 75 and an inner race 77. The latter similarly to the race 64 is extended in the form of a collar and arranged to slide freely on a bearing sleeve 78 which, like the sleeves 65 and 73, is renewable. The sleeve 78 is held in engagement at one end with a shoulder 79, provided by an enlargement in the diameter of the shaft 33, by means of a disc 80 at its other end bolted, as at 81, to the free end of the shaft 33. This also forms part of the subject matter of the copending application above mentioned. The loose rings 82 serve, in this instance, the same function as the rings 69; to feed lubricating oil onto the sliding joint between the sleeve 78 and the race 77. It is apparent that the arrangement provides for the compound movement of the shaft 33 by the sliding of the sleeve 78 in the race 77 and the rotation of the inner race relative to the outer race.

Referring now to Fig. 4, it will be seen that the opposite end of the shaft 33 from

the end previously under consideration has similar provisions in the bearing 34 for permitting simultaneous rotation and reciprocation of the shaft in anti-friction bearings.

5 A pair of caps 83 are bolted to the opposite sides of the bearing 34 and clamp the outer race 84 between them in an obvious manner. The bearing balls 85 are held between the outer race 84 and an inner race 86 sliding 10 on the bearing sleeve 87. This sleeve is held in engagement with the shoulder 88 by a spacing sleeve 89. The latter is in turn held in place by the inner race 90 of an anti-friction bearing within the thrust collar 38. The 15 sleeves 89 and 87 are interchangeable in like manner to the sleeves 65 and 73, as covered in the copending application. The inner race 90 is held in place by a collar 91, secured as by means of a tapered pin 92 to the 20 free end of the shaft 33. The outer race 93 for the balls 94 is held within the thrust collar 38 behind a cap 95 which bolts on the end of the collar 38. It will thus be seen that the provision of anti-friction bearings 25 is extended throughout the machine so far as practicable with a saving in operating costs and an increase in general efficiency.

I claim:

1. A machine as set forth in claim 5 30 wherein the shaft bearing supports on the machine frame members are vertically adjustable whereby to adjust the drum with its shaft according to the work to be handled, said counterbalancing means for said rocker arm being practically unaffected by such vertical adjustment of said shaft with its bearings by reason of the fact that the adjustment is slight.

2. A machine as set forth in claim 6 40 wherein the shaft bearing supports on the machine frame members are vertically adjustable whereby to adjust the drum with its shaft according to the work to be handled, said pivotal mounting for the rocker arm 45 with the yielding counterbalancing means therefor being arranged to be practically unaffected by the vertical adjustment of said shaft by reason of the fact that the adjustment is slight.

50 3. A machine as set forth in claim 7 wherein the drum shaft bearings are vertically adjustable relative to the frame elements to correspondingly adjust the drum relative to the work, the counterbalancing 55 means in connection with said link pivotally connected with the rocker arm being arranged to be practically unaffected by the endwise movement of said arm required in the vertical adjustment of said shaft by reason of the fact that the adjustment is slight.

4. In a machine of the character described, the combination of a pair of spaced frame elements, a shaft received in bearings in said elements and carrying a rotating abrading 65 drum operating between said elements, a

rocker arm, a thrust collar on said shaft having pivotal connection with said arm, a pair of links pivotally connected with said arm at points spaced lengthwise of the latter, one of said links providing a floating pivotal mounting for said arm on the machine frame and the other of said links having means for communicating a thrust thereto to rock said arm on its pivotal mounting whereby to communicate endwise oscillation to said shaft 70 through the thrust collar thereon, and means in connection with one of said links for counterbalancing the weight of said rocker arm whereby to eliminate the weight thereof from the thrust collar and hence from said shaft, both of said links being arranged by slight oscillation to permit straight line motion of the end of said arm pivotally connected with the thrust collar, said drum shaft being vertically adjustable with its bearings 75 relative to the machine frame whereby to correspondingly adjust the drum relative to the work, and said counterbalancing means being arranged to be practically unaffected by the accompanying endwise movement of said arm by reason of the fact that the adjustment is slight.

5. In a machine of the character described, the combination of frame members, a shaft supported by the latter and carrying an abrading drum for rotation between the frame members, a thrust collar on one end of said shaft, a rocker arm having a pivotal connection with said collar at its upper end, a link providing a floating pivotal connection for said arm with the one frame member to permit straight line motion of the upper end of said arm, another link having connection with said arm for rocking the same to communicate reciprocatory movement to said shaft, and means cooperating with one of said links to cause the frame to assume the weight of said arm whereby to keep the weight thereof off the thrust collar.

6. In a machine of the character described, the combination of frame members, a shaft supported thereby and carrying an abrading drum for rotation between the frame members, a thrust collar on one end of said shaft, a rocker arm having a pivotal connection with said collar at its upper end, a link providing a floating pivotal connection for said arm with one of said frame members whereby to permit straight line motion of the upper end of said rocker arm, another link having connection with the lower end of said rocker arm for rocking the same so as to communicate reciprocatory movement to said shaft, and a spring reaching from a suitable support to one of said links to yieldingly assume the weight of said arm and thus keep this weight off the thrust collar.

7. In a machine of the character described, the combination of frame members, a shaft supported thereby and carrying an abrading

drum for rotation between the frame members, a thrust collar on one end of said shaft which projects beyond one of the frame members, a vertically disposed rocker arm 5 having the upper end thereof pivotally connected with said collar, a link pivoted at one end on the last mentioned frame member and at the other end on said rocker arm intermediate the ends of the latter, providing a 10 floating pivotal mounting for said arm to permit straight line motion of the upper end thereof, spring means associated with said link for counterbalancing said rocker arm to relieve the weight thereof from the thrust collar, a second link having pivotal connection with the lower end of said rocker arm for communicating rocking motion to said arm and thereby reciprocatory movement to said shaft, and means for communicating 15 reciprocatory movement to the last mentioned link.

8. A machine as set forth in claim 7 including a bracket on the frame member having the first mentioned link pivoted with respect thereto, the rocker arm counterbalancing means comprising a compression spring acting between said bracket and the lower side of said link.

9. In a sanding machine comprising a pair 30 of frame members, and a shaft supported thereon and carrying an abrading drum for simultaneous rotation and reciprocation between the frame members; a thrust collar on one end of said shaft for transmitting reciprocatory movement thereto, a rocker arm 35 pivotally suspended from said collar, means for pivoting the rocker arm relative to the frame for rocking movement, the said means permitting a certain amount of up and down 40 movement of the rocker arm in the rocking thereof to provide for straight line motion of the upper end thereof with the thrust collar, means for assuming the support of the rocker arm whereby to relieve the thrust collar 45 of this weight and thereby provide for smooth operation of the shaft, and means for rocking the rocker arm, the means for assuming the weight of the rocker arm comprising spring means acting between the arm and the frame, the same being yieldable to 50 permit the up and down movement of the rocker arm.

In witness of the foregoing I affix my signature.

PETER A. SOLEM.
